COMBUSTION GAS HEATER APPARATUS
FOR MULTITEMPERATURE AIR SUPPLY
FOR FURNACES

John H. Cruise, Linden, N.J., assignor, by mesne assignments, to Combustion Engineering-Superheater, Inc., a corporation of Delaware

Application February 5, 1948, Serial No. 6,469

4 Claims. (Cl. 110—56)

1

This invention relates to heat exchangers and particularly to air heaters used in combination with heat exchange apparatus, such as a steam generator, from which the fuel gases serve as a heating medium for the air for combustion and in which there are burned at least two fuels having widely different characteristics.

The fuels here considered may require entirely different burning means and one of the burning means may limit the temperature of the air for combustion far below that required by the other; moreover, either one or the other of the fuels may be burned separately or both may be burned at the same time.

It is an object of this invention to provide an improved air heater that will, in a single unit, efficiently provide the above mentioned widely different combustion air temperatures for the different burning means whether either one or the other of said fuels is being burned or both are burned at the same time.

Additional objects of the invention will appear from the following description of one preferred embodiment thereof when taken in conjunction with the accompanying drawings wherein:

Figure 1 is a diagrammatic vertical sectional view of an air heater associated with a steam generator provided with two separate burning means for burning separate fuels;

Figure 2 is a transverse section of the air heater similar to Figure 1, taken on line 2—2 of Figure 4;

Figure 3 is a half section of the air heater taken on line 3—3 of Figure 2; and

Figure 4 is a half elevation of the air heater viewed from line 4—4 of Figures 1 and 2.

The illustrative system represented by Figure 1 includes a furnace 1 included in the steam generator there shown. A first fuel, such as coke or the like, is fired in this furnace either on a traveling grate stoker 2 or in other conventional manner; while a second fuel, such as gas (blast furnace or other), is delivered to the furnace by means of burner 3. Associated with the furnace is boiler 4 of well known construction having top and bottom drums 5 and 6 interconnected by a bank of tubes 7. Baffles 8, 9 and 10 direct the gases leaving the furnace downwardly and then upwardly through the boiler. An offtake 11 directs the flue gases through the breeching 12 to the top of the air heater 13 whence the gases pass downwardly through the tubes of tube bank 14 and leave the air heater at the bottom of said tube bank through flue 15.

The fuel for the stoker 2 is delivered through

2

hopper 16 on to the traveling grate and the blast furnace gas is delivered to the burner 3 via duct 17. The duct 17 adjacent the furnace wall is enclosed by an air chamber 18 through which pre-heated air for combustion from the air heater is delivered into the furnace via conduit 19. Air for combustion to the stoker 2 is delivered from the air heater 13 through conduit 20 to the air compartments 2a of the stoker.

As illustratively shown in Figures 1—2—3—4, the air heater 13 comprises an enclosure including front and rear walls 21 and 22, end walls 23 and top and bottom walls 24 and 25. The top and bottom walls include tube sheets 26 and 27 which extend for the full width of the air heater between the end walls 23 but are spaced from the front and rear walls 21 and 22 (as Figure 2 indicates). A bank of tubes 14 for flue gas conduction are fastened into the tube plates and likewise extend for the full width of the air heater between end walls 23 (see Figures 3—4) and are spaced from the front and rear walls 21 and 22 (see Figure 2).

Spaced transversely of the tube bank are baffles 28, 29 and 30. Top baffle 28 extends from the front wall 21 and across the tube bank 14. Central baffle 29 extends from the rear wall 22 across the tube bank 14 and stops in alignment with the front wall 21. Lower baffle 30 extends from the front wall 21 across the tube bank 14. Between baffles 28 and 30 there is an opening provided in the front wall 21 to which is connected a duct 31 through which the air to be heated is directed into the air heater. This air supply duct is best shown in Figure 2.

One of the heater end walls 23 is provided with an opening 32 to which the conduit 19 is connected for conveying air to the blast furnace gas burner 3. This end wall 23 is further provided with an opening 33 to which a by pass conduit 34 is connected for conveying heated air into the conduit 19 (see Figure 1) leading to the gas burner 3. The heater's bottom wall 25 is provided with an opening 35 to which is connected the conduit 20 (again see Figure 1) for delivering heated air for combustion to the stoker 2. A by pass damper 36 is provided in baffle 30 (see Figures 1—2) for short circuiting air delivered to the air heater from duct 31 directly into conduit 20. Conduit 20 is provided with damper 37. Conduits 19 and 34 are provided with dampers 38 and 39 respectively.

In operation the hot gases from the breeching 12 pass downwardly through the tubes of air heater tube bank 14 and out through flue 15.

The hottest gases therefore pass through the upper portion of the air heater and the cooler gases through the lower portion. Air for combustion enters the air heater via duct 31 and is divided by partition 29 into an upper and lower portion. The upper portion passes transversely across the tube bank 14, thence upwardly in the chamber between the tube bank and rear wall 22, thence transversely of the tube bank into the off-take chamber 32 between the tube bank and the front wall 21 and thence via conduit 19 to the gas burner 3.

The lower portion of the air passes transversely across the tube bank, thence downwardly in the chamber between the tube bank and the rear wall 22, thence transversely back across the tube bank into the offtake chamber 33 between the tube bank and the front wall 21 and thence into the conduit 20 to the stoker. Should the stoker air become too warm it may be tempered by opening damper 36 and admitting some of the cooled air directly into the heated air below.

As described, the air heater is designed in two sections, an upper and lower section. Within the upper section the air flows generally upwardly in counterflow to the downward gas flow and in the lower section the air flows generally downwardly in parallel flow to the gas flow. The air for combustion to the gas burners is passed over the tubes of the upper section containing the greater amount of heating surface and thereby reduces the heat carried by the gases to the lower section. The air temperature obtainable from the lower section is thereby held to a limit permissible for operation of stoker 3. The air temperature leaving the upper section for the gas burner 3 is relatively high, the burner construction being such as to permit a high temperature.

When burning both blast furnace gas and coke at the same time, in any proportions of these fuels, the air heater is so proportioned that the air temperature leaving the lower section will not exceed the safe limit for the stoker. Moreover, when coke alone is being burned, the rating of the steam generator is such that the flue gas entering the air heater is reduced to the temperature where the air for combustion from the heater is again at a temperature safe for use in stoker operation.

It is possible to obtain a substantially greater steam output from the steam generator when burning gas than when burning coke and it may be desirable to obtain higher ratings than those designed for when burning blast furnace gas alone. The limiting element for such higher ratings is the static pressure developed by the forced-draft fan (not here shown) for supplying the furnace 1 with air for combustion by way of heater 13 and inlet duct 31. Under these circumstances some of the air for combustion to burner 3 may be directed through the lower portion of the air heater and thence carried via conduits 34 into conduit 19 and thence to the gas burner. In this case the damper 39 in conduit 34 will be opened and the damper 37 in conduit 20 will be closed so that no air will pass to the stoker.

By thus directing the air through the air heater 13 through both the upper and lower sections thereof, the flow area for the air is materially increased and consequently the resistance to flow materially reduced. This reduces the pressure against which the forced draft fan is obliged to operate and thereby increases its ca-

pacity and therewith the rating of the steam generating unit.

While the preferred embodiment of my invention has been shown and described, it will be understood that changes in construction, combination and arrangement of parts may be made without departing from the spirit and scope of the invention as claimed.

I claim:

1. In a heat exchanger, the combination of a chamber, a plurality of conduits extending lengthwise therethrough, means for flowing a heating gas through said conduits from the gas-entering or high-temperature end of the chamber to the gas-exit or reduced-temperature end thereof, a plurality of baffles spacedly positioned between the two chamber ends to form within the chamber a plurality of transverse passes serially extending back and forth across the exterior surfaces of said conduits, an inlet duct for directing air to be heated into each of an intermediate pair of said transverse passes remote from the transverse passes at the extreme chamber ends and substantially midway therebetween along the conduit lengths, partition means between the two passes in said inlet pair for causing a portion of said incoming air to flow from said intermediate inlet through a first series of chamber passes leading to said high-temperature chamber end and another portion of the incoming air to flow from the inlet through a second series of chamber passes leading to said reduced-temperature chamber end, a first outlet duct connected to the extreme-end pass at said high-temperature chamber end to take therefrom air that is heated to the highest temperature, a second outlet duct connected to the extreme-end pass at said reduced-temperature chamber end to take therefrom air that is heated to a lower temperature, and means for at times by passing a portion of the lower-temperature air from said second outlet duct into the high-temperature air in said first outlet duct.
2. In a heat exchanger, the combination of a chamber, a plurality of conduits extending lengthwise therethrough, means for flowing a heating gas through said conduits from the gas-entering or high-temperature end of the chamber to the gas-exit or reduced-temperature end thereof, a plurality of baffles spacedly positioned between the two chamber ends to form within the chamber a plurality of transverse passes serially extending back and forth across the exterior surfaces of said conduits, an inlet duct for directing air to be heated into each of an intermediate pair of said transverse passes remote from the transverse passes at the extreme chamber ends, partition means between the two passes in said inlet pair for causing a portion of said incoming air to flow from said intermediate inlet through a first series of chamber passes leading to said high-temperature chamber end and another portion of the incoming air to flow from the inlet through a second series of chamber passes leading to said reduced-temperature chamber end, a first outlet duct connected to the extreme-end pass at said high-temperature chamber end to take therefrom air that is heated to the highest temperature, a second outlet duct connected to the extreme-end pass at said reduced-temperature chamber end to take therefrom air that is heated to a lower temperature, a by-pass conduit interconnecting said first and second outlet ducts, and dampers in said ducts and in said conduit for independently regulating the flow of air through

said first and second series of chamber passes and through the by-pass conduit.

3. In a system comprising a furnace that is provided with a gas burner and a stoker for respectively burning in the furnace a gas and a solid fuel either simultaneously or separately, the gas burner delivering combustion air to the gas at a temperature higher than the combustion air delivered by the stoker to its fuel, an air heater having tubular elements, a flue connecting the furnace offtake to the tubular elements for the flow of hot gases therethrough from the hot or gas entrance and to the cold or gas exit end, and a heat exchange casing for combustion air to be heated enclosing said tubular elements and extending longitudinally thereof, the combination of a partition located generally centrally of said tubular elements and extending transversely thereof within said casing to divide the casing into a high temperature heat exchange compartment adjacent said hot or gas entrance end of the tubular elements and a low temperature heat exchange compartment adjacent said cold or gas exit end of the tubular elements, air inlet means for admitting the aforesaid combustion air to be heated into said casing adjacent said transverse central partition and on both sides thereof whereby the admitted air enters both of said compartments adjacent the partition location longitudinally of the tubular elements and thence flows through those compartments in two separate streams, means forming a heated air outlet from said high temperature compartment of the casing and another heated air outlet from said low temperature compartment which two air outlets respectively are located adjacent the hot or gas entrance end of said tubular elements and adjacent the cold or gas exit end of those elements, a first conduit connecting the air outlet adjacent the hot end of the elements to the gas burner, a second conduit connecting the air outlet adjacent the cold end to the stoker, a by-pass conduit interconnecting the first and second conduits, and dampers in each of the aforesaid conduits for independently regulating the flow of air from the heater's hot end outlet to said gas burner and of air from the heater's cold end outlet to said stoker and of air from the cold end outlet to the hot end outlet through said by-pass.

4. In a system comprising a furnace that is provided with a blast furnace gas burner and a traveling grate stoker for respectively burning in the furnace blast furnace gas and coke either simultaneously or separately, the gas burner delivering combustion air to the gas at a temperature higher than the combustion air delivered by the stoker to the coke, an air heater having tubular elements, a flue connecting the furnace offtake to the tubular elements for the flow of hot
